UNITED STATES PATENT OFFICE.

PAUL R. VOGEL, OF CHICAGO, ILLINOIS.

CABINET.

1,160,218.

Specification of Letters Patent. Patented Nov. 16, 1915.

Application filed November 16, 1914. Serial No. 872,275.

To all whom it may concern:

Be it known that I, PAUL R. VOGEL, a citizen of the United States, residing in Chicago, in the county of Cook and State of Illinois, have invented certain new and useful Improvements in Cabinets, of which the following is a specification.

This invention relates to cabinets of the type designed for the storing and display of post cards and similar articles, and has for its object, a construction whereby the cabinet may be closed without re-arranging or disturbing the articles normally displayed thereby.

It is also a further object of the present invention to provide a combined storing and display compartment in the cabinet having a specially designed series of shelves whereby the angularity of the articles displayed may be adjusted for the purpose of regulating the display features of the cabinet.

With the above and other objects in view, this invention consists in the construction, combination, and arrangement of parts, all as hereinafter more fully described, claimed, and illustrated in the accompanying drawings, wherein:

Figure 1 is a perspective view of the cabinet forming the subject-matter of the present invention upon a suitable support, said cabinet being closed; Fig. 2 is a front elevation of the cabinet illustrating the same open for display purposes; Fig. 3 is a horizontal section along line 3—3 of the Fig. 2, to illustrate the arrangement of the compartments of the cabinet and particularly the central compartment; Fig. 4 is an enlarged detailed front elevation of the central compartment; Fig. 5 is a vertical section along line 5—5, Fig. 4, to illustrate the details of constructions of the central compartment and the adjustability of the shelves therein; and Fig. 6 is a perspective view of one of the shelves arranged for use in the central compartment illustrated in Figs. 4 and 5.

Reference being had more particularly to the drawing, 10 designates the body of a cabinet open at the front and provided with the doors 11. The inner faces of the doors 11 are provided with a series of pockets 12, designed for the reception of post cards and the like, and which are arranged in any suitable combination. The side walls 13 of the cabinet are likewise provided with pockets 14 as is also the back of the wall 15.

The central compartment is formed in combination with a back wall 15 by the partitions 16 which project from the back wall parallel to the side walls 13, said partitions being approximately equal in width to said side walls. The outer faces of the partitions 16 are provided with display pockets 14 similar in construction to the display pockets 14 carried by the back wall 15, side walls 13, and the doors 11. This central compartment is designed primarily to provide a place for storing and displaying post cards or similar articles in such manner that one or more of such articles may be readily removed from the central compartments and the shelving adjusted to regulate the display. To this end, the partitions 16 are provided on their inner faces adjacent to the rear wall 15 of the cabinet with spaced lugs or projections 17. There is one lug secured to each partition 16 in the same horizontal plane as the corresponding lug upon the opposite partition 16, said lugs or projections 17 being designed to support the rear edge of the shelves mounted in the central compartment inclosed by the partitions 16. The forward vertical edge of each partition 16 is provided with a beveled face 19 which terminates in its upper end in the curved surface 20 and at its lower end in a right-angular beveled surface 21. These three surfaces, viz., the beveled surface 19, the curved surface 20, and the beveled surface 21 in combination form a notch or recess in which is mounted the forward edge of the co-operating shelf of the central compartment as will be hereinafter more fully described.

The curved surface 20 of each projection 18 is horizontally aligned with the corresponding lugs or projections 17 so that if the forward edge of the body of the shelf terminates at the curved surface 20, the shelf will rest in a horizontal plane, whereas, if the forward edge of the body of the shelf rests flush with the beveled surface 21, the shelf will rest at an angle to the vertical plane. To accomplish this, the shelf comprises a plate 22 provided along its rear edge with the finger depression 23, and having its forward edge bent at an acute angle to the body of the plate 22 to form the flange 24, said flange having a finger depression 25 centrally located in its edge. In Fig. 5, the utility and adjustment of the shelf illustrated in Fig. 6 is clearly illustrated. The first shelf at the upper end of

Fig. 5 illustrates the rear edge of the plate 22 resting against the rear wall 15 of the cabinet, while the body of the shelf rests flush against the beveled surfaces 21 of the coöperating projections 18. The bend between the plate 22 and the flange 24 rests in the angle between the surfaces 19 and 21 of the projections 20. In this manner, the flange 24 rests approximately parallel to the rear wall of the cabinet, and consequently cards or like articles placed upon the plate 22 are so located that their forward edges rest flush against the face side of the flange 24 and their rear edges are so aligned that they may be readily removed individually from the shelf. If it is desired, the shelf may be tilted to the position shown in dotted lines in Fig. 5 so that the flange 24 may rest flush against the surfaces 19, thus while maintaining the relative position of the cards, reduces the perspective and presents a better display. If it is merely desired to use the shelf for storing purposes and not for display purposes, or 25 a combination of both, the position of the shelf is reversed as is illustrated by the lower shelf in Fig. 5, so that the edge of the flange 24 rests upon the inclined or beveled surfaces 21 of the corresponding projections 18 and the flange itself rests flush against the beveled surface 19 of said projections. This permits the rear edge of the plate 22 to rest upon the coöperating projections or lugs 17, thus causing the shelf to assume a horizontal position. The finger 30 depressions 23 and 25 permit the shelf to be readily adjustable.

It is obvious, therefore, that the present invention provides a means for not only 40 storing post cards, booklets, novelties, and the like, but permits them to be displayed

and protects these articles from dust, flies, damaging light, etc. By closing the doors 11, it is possible to store these articles without damaging them, while by opening the doors 11, a large display, normally occupying little or no space, is created.

In addition to the foregoing, the base 26 of the cabinet is provided with the drawers 27, whereby surplus articles may be stored.

While the preferred form of the present invention has been described and illustrated, it is to be understood that many changes may be made in the details of the construction without departing from the spirit and scope thereof.

What is claimed is:

1. Shelving comprising side partitions, lugs secured to said side partitions at their rear edges, projections secured to said partitions at their forward edges having a plurality of irregular surfaces, and shelves coöperating with each set of lugs and projections, the shelves coöperating with the irregular surfaces aforesaid for regulating the angularity and adjustability thereof.

2. A pair of horizontal projections having outwardly beveled surfaces terminating in curved surfaces at their upper ends, and in right angular beveled surfaces at their lower ends, supports horizontally aligned with the curved surfaces aforesaid, and shelves coöperating with said projections and said supports.

In testimony whereof I have hereunto affixed my name in the presence of two witnesses.

PAUL R. VOGEL.
